UNITED STATES PATENT OFFICE.

HARRY R. FELTON, OF PHILADELPHIA, PENNSYLVANIA, ASSIGNOR TO FEDERAL CONTAINER COMPANY, OF PHILADELPHIA, PENNSYLVANIA, A CORPORATION OF PENNSYLVANIA.

LINOLEUM CONTAINER.

Application filed March 21, 1924. Serial No. 700,758.

To all whom it may concern:

Be it known that I, HARRY R. FELTON, a citizen of the United States, residing at Philadelphia, county of Philadelphia and State of Pennsylvania, have invented a new and useful Improvement in Linoleum Containers, of which the following is a full, clear, and exact description, reference being had to the accompanying drawings, which form a part of this specification.

In the packing of linoleum for shipment, much difficulty has been experienced in properly protecting the goods and especially the ends. If the package is subjected to rough handling, the edges of the linoleum are liable to breakage, thereby seriously damaging it. Indeed, to avoid injury, the linoleum is often shipped in wooden boxes or crates, which are relatively expensive.

The object of my invention is to provide a container so constructed, and the parts whereof are so assembled, that it may be made of pasteboard, or similar flexible and cheap material, but which will afford practically absolute security against injury to the contents and particularly against breakage of the edges. The material that I prefer to use is that form of corrugated pasteboard which comprises two flat sheets spaced apart by a corrugated sheet; but it is to be understood that the invention comprises the construction of the container and is not limited to the use of any particular material.

A preferred embodiment of the invention is shown in the accompanying drawings, in which—

Fig. 1 is a plan view of a sheet of corrugated pasteboard scored preparatory to bending it into tubular form to provide the body of the container.

Fig. 2 is a plan view of one of the end closures before bending down the wings.

Fig. 3 is a cross-section through the body of the container.

Fig. 4 is a side view of one of the end closures after it is bent into shape over the end of a roll of linoleum.

Fig. 5 is a similar view of the double end closure.

Fig. 6 is a longitudinal sectional view of one end portion of the completed container.

Fig. 7 is a side view of the finished container.

The body of the container is made of a sheet *a* of corrugated pasteboard scored along parallel lines (see Fig. 1) and preferably at right angles to the direction of extension of the corrugations. The sheet is then bent on the scored lines and formed into an open-ended polygonal tube (approximating a cylinder) with the end flaps overlapping (see Fig. 3). The tubular body is closed by end closures of the same material, each comprising a central head *b* and radiating wings *c* (see Figs. 2 and 4). The head is of a diameter approximating that of the body. The closure is applied to the body by bending the wings *c* at right angles to the head and sliding them within the body. Preferably the closure is applied to the roll of linoleum *x* and the roll, with the end closures applied thereto, together inserted into the container body. Additional security is afforded by providing two closures at each end; each comprising a flat head and spaced-apart depending wings. The head *d* of the second closure rests against and outside the head *b* of the first closure and the wings *e* of the second closure occupy the space between the wings *c* of the first closure. See Fig. 5.

It is preferred to make the container body of octagonal form and to provide each end head with four wings corresponding in width to the width of each flat section of the tube and to have the light wings of the two end heads engage the respective sections of the tube; but while this is desirable, it is not essential. The outer head *d* should be of slightly greater diameter than the inner head *b*, so that the depending wings *e* of the outer closure may be more readily bent down over the adjacent edges of the inner head.

The overlapping edges of the tubular body are held together by means of a fabric strip *f* extending longitudinally along and over the exposed joint and glued to the body, as shown in Fig. 3.

After the end heads are applied to the tubular body, each head and the adjacent end portion of the body are covered with flexible material *g*, as, for example, a sheet of burlap. See Figs. 6 and 7. Steel encircling bands of strips *h* are then applied to the container. I have shown two bands encircling each burlap-covered end portion of

the container and a single bend encircling a midway part of the container.

While I have described the container as intended for use in the packing and transportation of linoleum, it may be adapted to other uses.

Certain features herein described are advantageous, although not essential to the embodiment of my invention in its broadest scope; and it is not intended to limit the invention to such features except in those claims that specifically recite them.

Having now fully described my invention, what I claim and desire to protect by Letters Patent is:

1. A linoleum container comprising a tubular body scored longitudinally along parallel lines and bent on the scored lines to form an open-ended polygonal tube, a separate end closure of bendable material comprising a flat head and flat wings bent at right angles to the plane of the head and extending within the tubular body in engagement with the inner wall thereof, said end closure adapted to be applied to the roll of linoleum and to be inserted, with the roll, within the tubular body as specified, a flexible cover enclosing the end head and the adjacent end portion of the tubular body, and a strap around the covered end portion of the body.

2. A linoleum container comprising a tubular body and separate end closures of bendable material, each closure comprising an end head and wings angularly disposed thereto and engaging the wall of the body, a flexible covering enclosing each end head and the adjacent end portion of the body and straps around the covered end portions of the body.

3. A linoleum container comprising an open ended tubular body and separate end closing means of comparatively stiff but bendable material comprising a plurality of end heads lying one upon another to form an end of a plurality of thicknesses and angularly disposed wings integral with the

end heads, the wings integral with each head being spaced apart and extending across the spaces between the other wings to form a substantially continuous enclosure of a single thickness.

4. A linoleum container comprising a tubular body and separate end closing means, the latter comprising two end heads lying one upon another and wings integral with and angularly disposed relatively to the respective heads, said wings extending within the tube, the wings of one head extending in the spaces between the wings of the other head.

5. A linoleum container comprising a sheet of bendable material scored along parallel lines and bent into the form of a polygonal tube, means to close the ends comprising end heads and integral angularly disposed wings corresponding in number and approximately in width to the flat sections of the tube, and inserted within the tube and fitting against said sections, and means to retain the body and end heads in assembled relation.

6. A linoleum container comprising a sheet of bendable material scored along parallel lines and bent into the form of a polygonal tube with overlapping end sections, two end closures at each end each comprising an end head and integral angularly disposed spaced-apart wings, the end heads lying one upon another and the wings of each head extending laterally across the spaces between the wings of the other head, all of said wings extending within the tube and engaging the inner wall thereof, a strip of material sealing the longitudinal overlapping edges of the body, a cover of flexible material enclosing the end closures and the adjacent ends of the body, and straps encircling the covered end portions of the body.

In testimony of which invention I have hereunto set my hand, at Philadelphia, Pa., on this 18th day of March, 1924.

HARRY R. FELTON
